UNITED STATES PATENT OFFICE.

FREEBORN F. RAYMOND, 2d, OF NEWTON, MASSACHUSETTS.

HEEL-NAILING MACHINE.

SPECIFICATION forming part of Letters Patent No. 398,846, dated March 5, 1889.

Application filed July 23, 1887. Serial No. 245,040. (No model.)

To all whom it may concern:

Be it known that I, FREEBORN F. RAYMOND, 2d, of Newton, in the county of Middlesex and State of Massachusetts, a citizen of the 5 United States, have invented a new and useful Improvement in Heel-Nailing Machines, of which the following is a full, clear, and exact description, reference being had to the accompanying drawings, forming a part of 10 this specification, in explaining its nature.

The invention relates to a machine organized to fasten heel-seats, spring-heels, or low heels to the soles of boots or shoes by a gang or group of fastenings simultaneously driven; 15 and it comprises various details of organization whereby a cheap and rapidly-operating machine is produced.

In the drawings, Figure 1 is a view in vertical section of a machine having the features 20 of my invention. Fig. 2 is a front elevation thereof. Fig. 3 is a section upon the line xx of Fig. 2 and a plan view of the parts below said line. Figs. 4 and 5 show a slight modification.

25 Referring to the drawings, A is the jack, a , the last or work support. The last, preferably, is adapted to be moved horizontally upon the bed a' .

B is the templet. It is supported upon a 30 lever or hinged plate, b , which is pivoted at its rear end, b' , to the standard or support b^2 , and is made vertically movable by means of the rod C, as hereinafter described.

E is a block supporting a gang or group of 35 drivers, e . It is mounted upon a block, e' , which is made vertically movable in the head or guideway e^2 by the lever e^3 , which is pivoted to the standard or support b^2 at e^4 . It is also operated by the rod C. The rod C is 40 moved by a crank or cam on the shaft c . I have represented it in Fig. 1 as operated by the cam c' , having a cam-groove, c^2 . This cam-groove receives a cam-pin, c^3 , attached to the lower end of the slide bar or rod c^4 . This rod 45 c^4 is made separate from the rod C, and is adapted to be connected and disconnected therewith, in order that the shaft c may be constantly rotated, without, however, imparting movement to the drivers and the templet.

50 B except when desired. The connection between the rod C and the slide bar or rod c^4 is represented as obtained by providing the

slide-bar c^4 with a flange or head, c^5 , and the rod C with a yoke, c^6 , the arms of which extend by the head c^5 , and are turned inward 55 upon the slide rod or bar c^4 . (See Fig. 1.) This provides the slide bar or rod c^4 with a movement on the end of the rod C, which movement, however, is not communicated to the rod C, unless the slide-block D is caused 60 to be inserted between the upper surfaces, d , of the horizontal section of the yoke c^6 and the under surface of the head c^5 , when the head is in its highest position, or in the position represented in Fig. 1. At that time the 65 block D, which is made in two parts, d d' , (see Fig. 1,) can be moved between these two parts, and upon the downward movement of the slide bar or rod c^4 the rod C will be drawn downward. The slide bar or block D is moved 70 into place by the lever d^2 , which is pivoted at d^4 , and it is automatically disengaged upon the upward end of the stroke of the slide bar or rod c^4 by means of the spring d^5 .

The rod C is connected by a pin, c^7 , directly 75 to the lever e^3 , back of its front end or point where it engages the slide-block e' . The rod C is connected with the templet-lever b in a manner to permit the rod to be moved to some extent in relation to the lever without 80 actuating it. This connection I have represented as obtained by forming a hole in the lever or pivoted plate b , through which the rod C extends, and mounting a spring, c^8 , between a collar fixed to the rod and the upper 85 surface of the lever or plate, and a spring, c^9 , between the lever and a collar fixed to the rod below it.

In operation the block D having been moved by the lever into position to cause a reciprocation or movement of the block e' and the templet, the rod C is moved downward, thereby drawing the templet B with it until the templet comes into contact with the upper surface of the sole or with the heel-blank 95 placed thereon, when it comes to a rest, but the rod C continues to move, drawing the block e' downward, causing the drivers to enter the holes in the templet and drive the nails therefrom into the heel and soles of the 100 boot or shoe.

In lieu of the construction above described the templet-lever b and the lever e^3 , to reciprocate the block carrying the drivers, may be

pivoted, respectively, at the points f , (see Fig. 4,) and the power for operating them applied at their ends. This power may be by means of a rod and cams such as I have already described, or by means of the cams, $f' f^2$, as represented in Fig. 4. The cam f' in this form of construction operates the lever e^3 by means of its cam-groove and a cam-pin on the end of the lever, which enters the groove, and the cam f^2 operates the lever b , the lever having a cam-pin, which enters a cam-groove in the cam-disk. A lever for thus operating the templet is described in my former application. The cams are mounted upon a vertical shaft, f^3 , which is rotated in any desired way, and I have represented it as turned by means of a horizontal shaft, f^4 , carrying a clutch and pulley, and which is connected with the vertical shaft by bevel-gears. (See Figs. 4 and 5.)

For loading the templet B, I use a movable loader, G, such as represented in Fig. 3, and movable laterally from one side of the templet into position over the templet to deliver nails thereto by means of a lever, g , pivoted at g' , and loosely connected with the nail-carrier block G. Suitable guides control the direction of movement of the block G, and suitable stops limit the extent of movement in both directions. There may be used to supply the block G with nails any suitable nail making and distributing or nail-distributing or nail-feeding mechanism, and many of those described in my various patents or pending applications can be employed.

The machine provides a simple, compact, and cheap organization for nailing heel-seats, spring-heels, or attaching low heels, or heels that do not require to be pricked or very much compressed before attaching.

In operation the boot or shoe is placed upon the last or work support and moved beneath the templet, and the templet provided with nails. The extent of movement of the templet is comparatively slight, so that the nails may be fed thereto, and the nail-carrier removed before the machine is set in operation, if desired;

and it is for this reason that I prefer to use the carrier G, operated by the lever g , as above specified, and to feed nails to the carrier G automatically, as the operator, standing at the front of the machine, can by a quick movement move the carrier from the nail-feeding device to the templet and allow it to discharge nails and immediately return it before the machine is set in operation. Whichever way is used, before the starting of the machine the templet is moved downward slightly, and this is followed immediately by the entrance of the drivers into the templet-holes and the driving of the nails, so that the templet reaching the end of its downward movement substantially at the same instant the nails are forced from the templet-holes by the drivers into the sole or heel. The drivers then lift, the templet moves upward slightly, and the templet comes to rest.

If a rand is to be attached, I prefer to use a removable rand-holding block like that described in my patent, No. 342,039.

Having thus fully described my invention, I claim and desire to secure by Letters Patent of the United States—

1. The combination of a last or work support, the vertically-movable templet B, the vertically-movable block e' , the gang of drivers e , carried thereby, and an actuating cam or crank connected with said block or templet by means of a connecting-rod having a yielding connection with the templet-support and connected with the block e' , to communicate its full movement thereto, substantially as described.

2. The combination of the templet or work support, the lever b , carrying the templet B, the lever b^3 , carrying the head e' and drivers e , and devices for simultaneously moving the said levers in the same direction, substantially as described.

FREEBORN F. RAYMOND, 2D.
